UNITED STATES PATENT OFFICE.

CYRUS A. CURTIS, OF BENTON HARBOR, MICHIGAN.

DRIVING MECHANISM.

1,230,682.

Specification of Letters Patent. Patented June 19, 1917.

Application filed October 11, 1916. Serial No. 125,019.

To all whom it may concern:

Be it known that I, CYRUS A. CURTIS, a citizen of the United States, residing at Benton Harbor, in the county of Berrien, 5 State of Michigan, have invented certain new and useful Improvements in Driving Mechanisms; and I do hereby declare the following to be a full, clear, and exact description of the invention, such as will enable others skilled in the art to which it 10 pertains to make and use the same.

This invention relates to driving mechanisms and has particular reference to driving mechanisms for washing machines.

15 The primary object of the invention is to provide an improved and simplified crank drive for washing machines, whereby rotary motion is converted into reciprocating motion.

20 It is also an object to provide in connection with the improved driving mechanism above mentioned a clutch for throwing the crank drive into and out of driving connection. In those power driven washing 25 machines which are known to me, and particularly those in which the wringer is mounted upon the washing machine and is also power driven, the driving mechanism has been comparatively complicated and 30 consists of so many parts which are subject to wear that constant difficulty is being experienced because of necessary repairs and renewal of parts. It is intended, therefore, in this invention to obviate this necessity to 35 the greatest possible extent, and to construct those parts which go into the improved mechanism of such character that there is comparatively little wear so that renewal of parts is necessary only at infrequent intervals.

40 With the above objects in view and such other objects relating to the details of construction as may hereinafter appear, my invention will now be fully set forth and described, reference being had to the accompanying drawings.

In the drawings:—

Figure 1 is a rear elevation of a washing machine having my invention applied 50 thereto,

Fig. 2 is a plan view of the mechanism,

Fig. 3 is a section on line 3—3 of Fig. 2, and

Fig. 4 is a section on line 4—4 of Fig. 2.

55 Referring more particularly to the drawings, 1 indicates the frame of a washing ma-

chine looking at the rear side thereof, the frame including a back board 2. This back board carries the greater part of the mechanism for driving the beaters or other devices within the machine. The usual wringer actuating mechanism 3 is suitably mounted upon the back board 2 and the shaft 4 vertically mounted in the brackets 5 has its lower end extended into geared relation with the 60 shaft 6 having bearings upon the lower transverse beam 7 of the frame 1. The shaft 6 also carries the drive gear 8 which meshes with a worm gear 9 upon a transverse shaft 10 which is mounted on the machine frame 70 and is directly connected to a motor 11, the latter being carried upon the lower transverse beam 12, also mounted upon the machine frame. Secured to the back board 2 by means of bolts 13 passed within a 75 widened flange is the bearing 14. The bearing 14 has a tubular element 15 which extends through the back board 2 and provides a bearing for a connecting shaft 16 whose inner end is provided with a cross head 17, 80 the latter being adapted to fit within a suitable socket upon the rock shaft of the washing machine. The outer end of the connecting shaft or stud 16 is provided with a reduced portion upon which is loosely mounted the crank arm 18 whose free end is connected with the drive gear 8 by means of a pitman 19, the latter having its upper end mounted upon the crank pin 20.

Interposed between the outer end of the 90 bearing 14 and the inner face of the crank arm 18 is a slideable clutch sleeve 21, which is externally grooved to receive the shipper 22. Below the clutch sleeve 21 the shaft 16 is provided with the longitudinal grooves 95 23 within which are slidably mounted the clutch pins 24. The inner surface of the sleeve 21 is annularly grooved as at 25 to receive the heads 26 of the clutch pins 24. Thus, the pins are continually connected 100 to the sleeve 21, in order to be longitudinally shipped, but are free to rotate with the shaft 16. The inner bearing surface of the crank arm 18 is longitudinally recessed to register at intervals with the grooves 23, so 105 that the free ends of the pins 24 may be engaged therewith to lock the crank arm to the shank 16. The shipper 22 is provided with a vertical stud 26' upon which is pivoted one end of a clutch lever 27, the intermediate 110 portion of the lever being mounted upon a bracket 28 secured to the back board 2 and

the outer end of the lever being provided with a hand grip 29. A slotted guide bracket 30 provides a means for limiting the movement of the hand lever and setting the latter in clutched or unclutched position.

It is obvious that when the motor 11 is started, the crank arm 18 is actuated through the medium of the worm-driven gear 8 and the pitman 19, the crank arm having a constant reciprocating action as long as the motor is being driven. In order to connect the crank arm with the connecting shaft 16, the lever 27 is actuated to throw the clutch sleeve 21 forward to bring the pins 24 into engagement with the recesses in the crank arm bearing, whereupon the washing element will be reciprocated in the usual manner.

It is apparent from the foregoing that I have simplified the usual form of power drive for washing machines and that the parts of the mechanism which are necessary to make up the drive are all of comparatively simple construction so that there is little chance for wear or breakage.

While the mechanism has been described as initially adapted for use upon washing

machines it is designed that the drive may be employed on any other machines or apparatuses where it is necessary to convert rotary into reciprocating motion.

What I claim as my invention is:

1. The combination with a drive shaft and a driven shaft, a drive gear actuated by the drive shaft, a crank arm loosely mounted upon the driven shaft, a pitman connecting said drive gear and said crank arm, and a clutch mounted upon the driven shaft for locking the crank arm to the latter.

2. The combination with a driving shaft and a driven shaft, of a drive gear actuated by the drive shaft, a crank arm loosely mounted upon the driven shaft, a pitman connecting said drive gear and said crank arm, a clutch sleeve slidable upon the driven shaft, key pins actuated by said clutch sleeve to lock the driven shaft to the crank arm, and means for actuating the sleeve.

In testimony whereof, I affix my signature, in the presence of two witnesses.

CYRUS A. CURTIS.

Witnesses:

JOHN L. CHADDOCK,
EDWARD T. LEITER.
